Primary Examiner — Michael A. Pratt(74) *Attorney, Agent, or Firm* — Cantor Colburn LLP(57) **CLAIM**

We claim, the ornamental design for a detonator module, as shown and described.

DESCRIPTION

FIG. 1 is a perspective view of a detonator module according to the new design;

FIG. 2 is a top-plan view of the detonator module of FIG. 1; FIG. 3 is a view from a first side of the detonator module of FIG. 1;

FIG. 4 is a view from an opposing second side of the detonator module of FIG. 1;

FIG. 5 is a bottom-plan view of the detonator module of FIG. 1;

FIG. 6 is a view from a first end of the detonator module of FIG. 1; and,

FIG. 7 is a view from an opposing second end of the detonator module of FIG. 1.
